GARMENT CONSTRUCTION

Perkins H. Bailey, New York, N. Y., assignor to
Talon, Inc., a corporation of Pennsylvania

Application April 1, 1940, Serial No. 327,123

3 Claims. (Cl. 2—74)

This invention relates to garments and, in particular, to the provision of improved front constructions in such garments, for instance, as are known as "housecoats" and "housedresses."

It is the primary object of this invention to provide such constructions embodying the features of low cost, attractive appearance, utmost ease and facility of ingress and egress, and convenience in adjusting the garments to forms or figures of widely varying sizes and proportions.

It is a further object of this invention to provide such constructions embodying a slide fastened closure, which is of relatively short length with respect to the length of the complete garment front opening provided by the garment front construction.

It is a further object of this invention to provide such constructions wherein an opening, in the front waist portion of the garment, is provided with a separating end slide fastener leading into an opening, adjacent and below the garment waistline, which last-named opening provides for substantial extension of the slide fastened closure and which last-named opening is provided with a tongue or gusset extending from edge to edge thereof.

It is a further object of this invention to provide such a construction wherein the gusset forms a wall of a pocket in the garment skirt portion.

It is a further object of this invention to provide such constructions, wherein the gusseted opening, which provides an extension of the slide fastened closure, is partly covered by an overlying portion of the garment waist portion.

It is a further object of this invention to provide such a construction wherein the lower end of the fastener, in the slide fastened closure, is in overlapping relationship to the skirt portion and gusset and substantially free of adjacent garment portions and readily accessible for facilitating manual disconnection of the lower ends of the slide fastener in opening the slide fastened closure.

It is a further object of this invention to provide, in such a construction, a new and improved front waist construction embodying a closure flap comprising a pair of longitudinally extending slide fastener stringer supporting strips or members secured to the waist portion of the garment at their upper ends only and provided with tie strings at their lower ends adapted, when the stringer supporting strips or members are connected by the slide fastener, to provide for adjustment of the garment waist portion while

maintaining the slide fastened closure snug against the waist portion and maintaining the front closure of the garment closed.

These and other objects and advantages of the invention will appear from the following description taken in conjunction with the accompanying drawings which form a part thereof, and will be pointed out in the appended claims.

In the drawings:

10 Fig. 1 is a front view of an illustrative garment embodying a garment front construction according to this invention, with the garment front closed;

15 Fig. 2 is a fragmentary view of the garment front construction of Fig. 1 with the garment front closure open;

20 Fig. 3 is a rear view of the illustrated garment construction of Figs. 1 and 2, the lower part of the garment skirt portion being omitted, as in Fig. 2;

25 Fig. 4 is a fragmentary front view of an illustrative modified form of garment construction, the garment front closure being closed and a part of the garment skirt portion being omitted in the interest of clearness;

Fig. 5 is a view similar to Fig. 4 of the embodiment of Fig. 4 with the front garment closure open;

30 Fig. 6 is a section taken substantially on the line 6—6 of Fig. 1;

Fig. 7 is a section taken substantially on the line 7—7 of Fig. 2;

Fig. 8 is a section taken substantially on the line 8—8 of Fig. 5; and

35 Fig. 9 is a fragmentary section taken substantially on the line 9—9 of Fig. 2.

This invention extends the use of slide fasteners to low cost garments, such as "housecoats" and "housedresses," where the use of other fastening means has formerly been dictated by the extremely rigid limitations imposed by the highly competitive nature of the low cost garment market.

Formerly, in the manufacture of garments such as "housecoats" and "housedresses," the provision therein of slide-fastened closures of such length as to provide the necessary and desirable large opening necessary for convenience of ingress and egress has been accomplished only with

40 the accompanying disadvantages of substantial, if not prohibitive, increase in garment cost. This has been particularly true in the highly competitive low cost garment field, where the increase of the price of a garment by a few cents has, quite often, been disastrous to the manu-

facturer of the garment in this highly competitive field.

Slide fasteners are sold by length and, for that reason, the use of a fastener of such length as to extend throughout the length of a closure of from 36" to 40" hitherto thought necessary for convenient ingress and egress, formerly, made the price of the slide fastener a substantial, if not exorbitant, factor in the sale price of the garment.

According to this invention, a relatively short slide fastened closure incorporating a slide fastener of short length and therefore, of low cost, is used in the waist portion of the garment. An extension of the slide fastened closure opening is provided in the skirt portion of the garment and gusset means is provided for closing this extension of the slide fastened closure opening. This structure achieves, by the use of a cheap slide fastener of short length, the advantages achievable heretofore only by the use of slide fasteners of far greater length and commensurately greater cost.

Considered in a different way, the front of the garment is provided with a closure opening of such length as to achieve the necessary and desirable convenience of ingress and egress. A part only of this closure opening is slide fastened by the use of a short cheap, separating end slide fastener. That portion of the closure opening which is not slide fastened, is closed by a gusset secured between the sides or edges thereof.

By the above, generally described structure, the above enumerated objects and advantages are achieved, as will be hereinafter pointed out in detail.

In the following description, for the sake of convenience, the rear portion of the garment extending downwardly from the upper end or neck thereof to the bottom of the skirt and from side to side, will be treated as a unit and designated the back panel. This back panel may, of course, be formed of a single piece of material or of a plurality of pieces of material secured together in any known manner.

That part of the front wall of the garment which forms the front wall of the waist portion of the garment, and which extends from the upper end or neck of the garment downwardly to the waistline of the garment, at least, and from side to side thereof, will be considered as a unit and designated the front waist panel. This front waist panel may, of course, be formed of a single piece of material or made up of a plurality of pieces of material secured together in any known manner. The front waist panel is provided with a slide fastened closure extending substantially from its upper end to its lower end.

The other part of the front wall of the garment which extends upwardly from the bottom of the garment to the waist line, at least, and from side to side of the garment, will be designated the front skirt panel. This front skirt panel forms the front wall of the skirt portion of the garment.

Conventional details of dressmaking such as stitching, seams, facings and the like which are not, in themselves, a part of this invention, will be omitted from the following description and are omitted from the drawings of this application in the interest of clearness of the disclosure.

Referring to the drawings in detail and with reference to Figs. 1, 2, 3, 6, 7 and 9, the back panel is generally designated 10, the front waist

panel is generally designated 11, and the front skirt panel is generally designated 12.

In the embodiment illustrated in Figs. 1, 2, 3, 6, 7 and 9, the front waist panel comprises a pair of panel portions 14 and 15, each having its upper and outer side edges secured in suitable manner to adjacent edges of the back panel 10.

The front skirt panel has its side edges secured, throughout their length, to adjacent edges of the back panel 10. At its upper end, the front skirt panel 12 is secured to the front waist panel 11 and is also provided at one side with a pocket slit 16 which slit is closed at its upper end. A slit 17, which is similar in appearance to pocket slit 16, is disposed at the opposite side of the upper end of the front skirt panel 12, but, unlike the pocket slit 16, this slit (hereinafter designated the closure slit) extends upwardly to the upper edge of the front skirt panel 12.

Above the pocket slit 16, the upper end of the front skirt panel 12 is secured at 16a to the lower end of the front waist panel portion 14 from the outer edge substantially to the mid-portion of the garment.

An optional collar facing 14a is secured to the inner edge of the front waist panel portion 14 and the inner edge of the closure slit 17. This collar facing 14a as shown in Fig. 2, extends downwardly on the inner edge of the slit 17, to the bottom of the closure slit 17 and thence upwardly on the outer edge of the slit 17 to the upper end of the front skirt panel 12 (Figs. 2 and 7). Those portions of the upper end of the front skirt panel 12 at each side of the closure slit 17, between the line of attachment designated 16a and the opposite side of the front of the garment, are free of attachment to the front waist panel 11.

Underlying that portion of the upper end of the front skirt panel 12, adjacent the pocket slit 16, is a pocket back wall 18 which is stitched to the overlying portion of the front skirt panel 12 and which has its upper edge secured to the front skirt panel 12 and front waist panel portion 14 and 16a, as shown in Fig. 2.

A gusset 19 of shape similar to the pocket back wall 18 is secured in like manner beneath the closure slit or pocket opening 17. That is, the outer side edge of the gusset 19 is secured to the skirt panel 12 and back panel 10 at the side seam of the garment (Figs. 6 and 7), the lower edge and a portion of the inner lateral edge are sewed to the overlying portion of the skirt panel 12, and the upper edge of the gusset 19 is secured to the lower end of the panel portion 15 at 19a.

The collar facing 15a which is generally similar to the above described collar facing 14a, extends from the upper portion of the neck of the garment downwardly along the inner edge of the front waist panel portion 15 and the gusset 19, as shown in Figs. 2, 6 and 7.

The front skirt panel 12 is provided adjacent the upper end of the closure slit 17 with complementary fastening means, such as the hook member 21 and eye member 20, as shown in Fig. 2. When the hook member 21 and eye member 20 are disconnected, as shown in Figs. 2 and 7, the garment closure extends to the lower end of the slit 17 substantially below the waistline of the garment. The closure slit 17 also forms the slit or opening of the lefthand pocket of the garment. This closure extension is closed at all times by the gusset 19 which also forms the back wall of the lefthand garment pocket of the garment.

In order to provide a slide fastened closure for the garment, a pair of longitudinally extending slide fastener stringer strips or facings 22 are secured at their upper ends only, as by stitching 23, to the shoulder portions of the garment at opposite sides of the neck opening to form a closure flap free of attachment to the garment except at its upper end. Each of these fastener stringer supporting members or strips 22 has secured to the inner edge thereof and extending upwardly part way from its lower end one of the stringers 24 and 25 of a separating end slide fastener. The stringer 24, for instance, carries the slider 26 and separating end retainer fitting 28 having therein a recess for receiving the pin member 29 carried at the lower end of the other stringer 25.

In order to secure the lower ends of the fastener stringer supporting members or strips 22 snugly against the underlying portions of the garment, a tie member or tie string 30 extends outwardly from the outer edge of each fastener stringer supporting member or strip 22 at its lower end. These ties 30 are adapted for extension backwardly around the waist portion of the garment and over the back panel 10, where they are tied or knotted as shown in Fig. 3, for accomplishing the dual purpose of maintaining the slide fastener stringer supporting members 22 in proper position, and for providing suitable adjustment of the waist portion of the garment when the front closure thereof is closed.

Considered in another way, the fastener stringer supporting members 22 may be said to comprise a longitudinal flap extending over the overlapped front closure portions of the garment, which flap is provided intermediate its width with a slide fastened closure embodying a slide fastener of the separating end type, by means of which the parts of the flap may be attached and detached. The ties or tie strings 30 may be considered as extending transversely from the lower end of this flap in opposite directions. That part of the closure opening which forms an extension of the overlapped front closure, below the waistline, is closed by the gusset 19 as described above.

In the modification illustrated in Figs. 4 and 5, the back panel is designated 40, the front waist panel is designated 41 and the front skirt panel is designated 42. These panels correspond, respectively, with the similar panels 10, 11 and 12 of the garment of Figs. 1, 2, 3 and 6 to 9 inclusive. The front waist panel 41 is made up of the right-hand portion 44 corresponding to the above described portion 14 and a left-hand panel portion 45 corresponding with the above described panel portion 14. The closure slit 47, which corresponds with the above described closure slit 17, extends downwardly from the upper end of the front skirt panel 42, a substantial distance, as shown in Fig. 4. The upper end of the front skirt panel 42 is secured to the lower end of the front waist panel 41 at each side of the closure slit 47, a slight spacing of the sides of the slit 47 being preferred in order to maintain free manual ac-

cess to the fitting 28 of the separating bottom end fitting of the slide fastener.

Underlying the closure slit 47 is a gusset 49 of generally triangular form, the inclined edges of the gusset 49 being secured to opposite side edges of the closure slit 47, as shown in Fig. 8, and the ends of the straight upper side being attached to the front waist panel portions 44 and 45 at opposite sides of the slide fastened closure.

It will be noted that in this embodiment, the slide fastener is secured directly to the inner edges of the front waist panel portions 44 and 45, and the ties or tie strings 30, provided in the first described embodiment, are omitted from the front of the garment. It is preferred that these ties be attached to the back panel of the garment, which corresponds with the above described back panel 10, or the side portions of the front waist panel 41, or to the adjacent upper end of the front skirt panel, at both sides, or, alternatively, attached to both.

The above-described embodiments are illustrative of the application of the broad principle described in my copending application Serial No. 325,992, filed March 26, 1940, to garments embodying a gusset closed extension in the skirt portion of the garment for a slide fastened closure in the waist portion thereof; the application of the broad principle of this invention to other types of garments, wherein the extension for the slide fastened closure is provided by a wrap-around closure extension in the skirt portion of the garment is described and claimed in my copending application Serial No. 326,705, filed March 29, 1940.

It is, of course, to be understood that the above description is merely illustrative and in nowise limiting and that I desire to comprehend within my invention all modifications included within the scope of the appended claims.

Having thus fully described my invention, what I claim as new and desire to secure by Letters Patent is:

1. In a garment of the class described, a garment front having therein a front opening extending downwardly from its upper end, an expandable gusset secured to the lower part of the edges forming said opening, and means including a separating end slide fastener secured to said edges from the top thereof to said gusset for closing that portion of said opening above said gusset and fastening together the edge portions of said opening immediately adjacent the upper edge of said gusset.

2. In a garment as in claim 1, said garment including a waist panel and a skirt panel, and said gusset being positioned in said skirt panel with its upper edge lying substantially at the waist line of said garment.

3. In a garment as in claim 1, said garment including a waist panel and a skirt panel, and said gusset comprising a triangular insertion in said skirt panel and constituting a pocket the mouth of which is the unclosed portion of said opening.

PERKINS H. BAILEY.
